CLAIM

The ornamental design for a tip for eye liner, as shown and described.

DESCRIPTION

FIG. 1 is a perspective view of a tip for eye liner showing the new design; and

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a cross-sectional view along line 7-7 of FIG. 2; and, FIG. 8 is a view of an tip for eye liner in an exemplary environment.

The broken line showing of the tip for eye liner in FIG. 8 is for environmental purposes only and forms no part of the claimed design.

1 Claim, 3 Drawing Sheets
